(57) **CLAIM**

The ornamental design for a burp bib support, as shown and described.

DESCRIPTION

FIG. 1 is an isometric view of the first embodiment of the burp bib support of this invention;

FIG. 2 is a top view of the first embodiment of the burp bib support of this invention;

FIG. 3 is a front view of the first embodiment of the burp bib support of this invention;

FIG. 4 is side view of the first embodiment of the burp bib support of this invention;

FIG. 5 is a back view of the first embodiment of the burp bib support of this invention;

FIG. 6 is an opposite side view of the first embodiment of the burp bib support of this invention;

FIG. 7 is bottom view of the first embodiment of the burp bib support of this invention;

FIG. 8 is an isometric view of the second embodiment of the burp bib support of this invention;

FIG. 9 is a top view of the second embodiment of the burp bib support of this invention;

FIG. 10 is a front view of the second embodiment of the burp bib support of this invention;

FIG. 11 is a side view of the second embodiment of the burp bib support of this invention;

FIG. 12 is a back view of the second embodiment of the burp bib support of this invention;

FIG. 13 is an opposite side view of the second embodiment of the burp bib support of this invention; and,

FIG. 14 is a bottom view of the second embodiment of the burp bib support of this invention.
